UNITED STATES PATENT OFFICE.

ANDREW LOCHHEAD, OF OAKLAND, CALIFORNIA.

DOOR SECURER.

Application filed January 31, 1927. Serial No. 164,736.

This invention relates to improvements in door-guards generally, but more specifically to devices designed for use in securing the doors of a room from being opened from the outside by unauthorized persons, and has particular reference to that class of door-securing devices shown and described in my issued Patent, No. 1,176,069, dated March 21, 1916. In this patent the adjusting means consisted of a cam lever adapted for ordinary doors. In actual practice it became apparent that cam members, in a device of this character, while satisfactory in a measure, failed to provide the necessary latitude of adjustment for doors of different thicknesses.

It is very desirable to provide for considerable adjustment in such devices, and I have, therefore, designed an improved and greatly simplified means for obtaining this adjustment to meet the varying requirements as above stated.

My present invention consists of but three parts of extremely simple form, one of which is threaded at one end and its complementary part carries a nut loosely mounted thereon. The nut is adapted to receive the said threaded end, thus providing for a considerable range of end-wise adjustment movement.

An important object of the present invention is to provide an improved door-securer having adjusting means adaptable for movement from a fractional part of an inch to several inches, and for positively holding said means in adjusted position.

Another object of my invention is to provide a device of the class designated that is very compact for carrying in the pocket of the clothing, extremely cheap to manufacture, durable, and of exceedingly rigid construction.

Still another object of the invention provides that it may be readily inserted between the edge of the door and the door-jamb of a room and whether the door thereof is provided with a mortise lock or not; the only requisite being that the jamb be provided with an ordinary lock-strike to receive the retaining member of the device.

In addition to the foregoing objects is the provision that when the device is in place, it holds the door firmly in the secured position and also prevents the same from rattling.

With the above and other objects in view

as will become apparent as the description proceeds, the invention consists in certain constructions, combinations and arrangements of parts that I shall hereinafter more fully describe and claim.

In the accompanying sheet of drawings:

Figure 1 is a horizontal sectional detail plan of a door-jamb and door shown in closed position and illustrating the application of my door-securer therewith;

Figure 2 is a side elevation of the invention per se, looking in the direction of the arrow 2 in Figure 1, the nut thereof being shown partly in section;

Figure 3 is a longitudinal mid-section of the device, the section being indicated by the line 3-3 of Figure 2; and

Figure 4 is a disassembled perspective view showing the various parts constituting the device.

Referring with greater particularity to the drawings, the numeral 10 designates a supporting bar constructed of thin steel of suitable gage and is provided with an offset inner end 11 adapted to engage the usual lock-strike 12 in the door-jamb 13. This bar 10 when in position as shown in Figure 1, rests flatwise against the face of the door-jamb in the clearance space between the jamb 13 and door 14 and does not hinder the free movement of the door when it is swung upon its hinges (not shown).

The bar 10 is provided centrally thereof with an elongated slot 15 extending approximately throughout two-thirds of its length, and has formed at its outer end a shank 16 having a plurality of teeth, or serrations, 17 and 18 cut in its upper and lower edges, forming threads adapted to be engaged by an internally threaded nut 19.

The door-engaging bar 20 is provided at its inner end with a lug 21 bent at right-angles to the body thereof, said bar being adapted to lie flat against the supporting bar 10, as shown in Figures 1, 2 and 3, and is adapted to be held in sliding contact therewith by means of a rivet 22 which engages in the slot 15 of the bar 10. The rivet has a head 23 slidingly contacting the outside surface of said bar 10 and is adapted to hold the bars together and in slidable relation to each other.

An additional guiding means is formed in the bar 20 and consists of a tang 24 punched from the body of the bar and adjacent the rivet 22, and is adapted to snugly extend in

to the slot 15 of the bar 10 to prevent any rotational tendency of said bars relative to each other upon the rivet 22 when not in use.

5 The outer end of the door-engaging bar 20 is provided with notched upper and lower sections 25 and 26, forming a nut-holding means adapted to retain the nut 19 in position upon the said bar and to hold it against 10 longitudinal movement thereon. The nut 19 also embraces the shank 16 of the supporting bar 10, and its threads 27 are adapted to engage the upper and lower threads, or teeth, 15 and 18 thereof, in such a manner that when the nut is rotated in one direction the bar 20 and its lug 21 are moved outwardly relative to the member 11 of the bar 10, and when rotated in the opposite direction the lug 21 travels toward said member 11, and is 20 thereby readily adjusted to bind against the face-edge of the door 14, as shown in Figure 1, to securely hold the door closed in its frame and thereby prevent the door from being opened from the outside of the room 25 by unauthorized persons.

It will be apparent from the foregoing description that I have provided a much more simple form of door-securing device than that shown in my former construction, 30 and have additionally provided a door-securing device with adjusting means adapting the device to operate through a considerable range of adjustment not possible of attainment with cam-actuated devices of this 35 character, and have also attained in the present construction, a device which has more positive and greater force resisting features, and one that cannot be worked loose by vibration caused by a person pounding or 40 pushing and pulling upon the door from the outside.

From the foregoing description taken in connection with the accompanying drawings, the advantages of the construction and 45 method of operation will be readily understood by those skilled in the art to which the invention appertains, and while I have described the principle of operation, together

with the device which I now consider to be the best embodiment thereof, I desire to 50 have it understood that the device shown is merely illustrative and that such changes may be made when desired, as fall within the scope of the appended claims.

Having thus described my invention I 55 claim as new and desire to secure by Letters Patent of the United States, the following:

1. A door-securer, comprising a supporting bar and a door-engaging bar, said supporting bar having a lock-strike engaging-member formed at its inner end and provided with a slot extending longitudinally therefrom, and said door-engaging bar having a door-engaging lug adapted to bear against the inside face-edge of the door, rivet means 65 to hold the said bars slidably together, spaced guide members carried by said door-engaging bar and being adapted to be engaged in said supporting-bar slot, the outer end of said supporting bar having a threaded shank and the outer end of said door-engaging bar bearing nut-holding means consisting of oppositely disposed notched edges, and said nut member being adapted to embrace said threaded shank to provide for the 75 longitudinal adjustment of said door-engaging bar relative to said supporting bar for binding the door in closed position.

2. In a door-securer, a supporting bar and a door-engaging bar, a rivet and a tang carried by said door-engaging bar, the said supporting bar being provided with a longitudinal slot for the reception of said rivet and tang for holding and guiding the bars with respect to each other, notches providing nut-holding means formed on the outer end of 85 said door-engaging bar and threads formed upon the corresponding end of said supporting bar, and a nut loosely carried by said nut-holding means and being adapted to embrace said supporting-bar threads to cause the longitudinal adjustment of said door-engaging bar relative to said supporting bar to 90 secure a door in the closed position.

In testimony whereof I affix my signature.
ANDREW LOCHHEAD.
